DESIGN FOR A DRAWER PULL

Earl M. Borchers, Rockford, Ill., assignor to
American Cabinet Hardware Corporation,
Rockford, Illinois, Rockford, Ill., a corporation
of Illinois

Application August 8, 1945, Serial No. 121,312

Term of patent 7 years

(Cl. D10—8)

To all whom it may concern:

Be it known that I, Earl M. Borchers, a citizen
of the United States, residing at Rockford, in the
county of Winnebago and State of Illinois, have
invented a new, original, and ornamental Design
for a Drawer Pull, of which the following is a
specification, reference being had to the accom-
panying drawing, forming a part thereof.

Figure 1 is a plan view of a drawer pull embody-
ing my new design.

Fig. 2 is a front elevational view of the same.

Fig. 3 is an underside elevational view of the
drawer pull.

Fig. 4 is an end elevational view.

The dominant features of the design reside in
the portion shown in full lines in the drawing.

I claim:

The ornamental design for a drawer pull, sub-
stantially as shown and described.

EARL M. BORCHERS.
